UNITED STATES PATENT OFFICE.

RALPH H. NORTON, OF CHICAGO, ILLINOIS, ASSIGNOR TO ACME STEEL GOODS COMPANY, OF CHICAGO, ILLINOIS, A CORPORATION OF ILLINOIS.

BOX-BAND STRETCHER.

1,262,082.

Specification of Letters Patent. Patented Apr. 9, 1918.

Application filed November 29, 1915. Serial No. 64,136.

To all whom it may concern:

Be it known that I, RALPH H. NORTON, a citizen of the United States, residing at Chicago, in the county of Cook and State 5 of Illinois, have invented certain new and useful Improvements in Box-Band Stretchers, of which the following is a specification.

In some instances it has been the practice in securing a band about a box or other 10 article to secure the ends thereof together by means of a buckle of some kind and in other instances the ends of the band are secured together without such device. My invention relates to a tool for drawing the 15 ends of a band for boxes and the like toward or past each other and thereby stretching the band and maintaining the ends in proper relation while they are being suitably secured. In the preferred form of the invention 20 the tool is adapted for fastening such a band by means of a buckle. In another form of the invention the tool is adapted to stretching bands in which no buckle is employed for securing the ends thereof together. In each instance, however, the tool 25 includes means for gripping both ends of the band and forcing them toward each other, in the one case, the pressure being applied to the buckle on one hand and directly 30 to the band on the other, and in the other case applied directly to both ends of the band. The construction of the device is simple, comprises few parts, is not apt to be broken or rendered inoperative and is 35 easily manipulated for the purpose in view.

In the accompanying drawings, I have shown and described two preferred forms of the invention, one of which is particularly adapted for use in tightening box 40 bands where a buckle is interposed between the two ends of the band for the purpose of securing them together, and the other of which is particularly adapted for use in connection with bands having no buckles 45 for uniting their ends. It is to be understood, however, that the specific disclosures are for the purpose of exemplification only and that the scope of the invention is to be ascertained from the following claims in 50 which I have endeavored to distinguish it from the prior art so far as known to me without, however, relinquishing or abandoning any part or feature thereof.

Referring now to the accompanying 55 drawings, Figure 1 is a side elevation of a

portion of a box with a strap or band applied thereto and that form of the device which is particularly adapted for use in connection with buckles in one of the positions which it assumes when being used; 60 Fig. 2 is a horizontal section upon the planes of the line 2—2 of Fig. 1, of the same device; Fig. 3 is a vertical section of the tool partly in elevation upon the line 3—3 of Fig. 2; Fig. 4 is a transverse section upon line 4—4 of Fig. 1, and Fig. 5 is an elevation of a box with a band applied thereto without any buckle and that form of my device adapted to apply such bands, a part of the latter being shown in vertical section 70 to better disclose the construction.

Referring first to Figs. 1 to 4 inclusive, the buckle A which the tool is particularly adapted and intended to apply is best seen in Fig. 2 and comprises substantially a thin 75 metal plate having a trapezoidal opening therein to receive the ends of the band. One end B of the band is thrust through the opening in the buckle from above and folded around the same and under the body of the 80 band and thereby securely attached to the buckle. The other end of the band is passed through the opening from below and bent backward around the inclined interior edge D and the inclined exterior edge E and beneath the buckle. In the drawing, however, the buckle is shown with the end B fully attached thereto and the end C inserted through the opening but not bent back around the edge D. This form of 85 buckle forms the subject-matter of an application for United States patent filed by me of even date herewith.

The tool comprises a main lever body 6 which is provided with means for grasping 95 one end of the box band and a link 7 for engaging and drawing the buckle toward the other end of the strap. The link 7 is pivoted to the main casting or barrel 8 of the tool at 9 near but above one end thereof 100 and extends laterally therefrom. The link is provided at its outer end with a head 10 comprising a thickened portion having a groove 11 formed longitudinally of the link therein which receives the box band or tie 105 adjacent the buckle. On the side of the head of the link nearest the lever and below the body thereof is a transverse slot or groove 12 which is adapted to receive the end edge of one of the buckles above de- 110

scribed after it has been applied to an end of a band, which latter extends through the groove 11 in the head, as above described. In order to prevent the buckle from accidentally turning upward, the link is also provided with a lug 7^a which is arranged above the plane of the slot and adapted to bear upon the upper face of the buckle. The pivoted end 13 of the link is curved upward slightly from the body thereof, as shown in Fig. 1, and is pivoted in a kerf or slot formed in the boss or projection 14 upon the lever member, by means of the pivot 9, to which reference has been made above. The lower end of the lever terminates in a foot or anvil 15 substantially at right angles to the body thereof and a reciprocable pin or bolt 16 extends through an opening in the boss or offset 14 of the lever and through a bore 18 (see dotted lines, Fig. 1) formed in an enlargement 19 of the casting or lever. The enlargement 19 is also slotted or formed with a pair of lugs 20 between which a hand lever 21 is pivoted at 22. A shoulder 23 is formed on the hand lever 21 just above and adapted to bear upon the upper end of the pin or bolt 18, the construction being such that when the handle 21 approaches the rigid handle 24 upon the lever the shoulder engages the bolt 18 and forces the same downwardly. A coiled spring 25 is interposed between the lower offset 14 and a transverse pin 26 on the bolt 18 and normally maintains said bolt in its upper position and out of engagement with the jaw 15. It will now be obvious that when the hand lever 21 is grasped in taking hold of the tool the shoulder 23 engages the upper end of the pin 18 and forces the same downwardly so that the lower conical end 27 of said bolt engages a slightly hollowed seat 28 upon the anvil 15, or if a band or the like is upon the anvil at the time it bends or raises a cup in the band by which latter and the pressure between the parts the lever is prevented from moving relatively to the band.

In operation the buckle is first secured to one end of the band in the manner above described and the link engaged with one edge of said buckle, the lever being engaged in the manner above described with the other end of the band. Upon grasping the rigid and pivoted handles 21, 24, as shown in Fig. 1, the tool is caused to grasp the band at a suitable point and the link being already engaged with the proper edge of the buckle and with the end of the band to which the buckle is attached extending through the buckle or passage through the head of the link, movement of the lever to the left, as shown in said figure, stretches the band tightly about the box or other article to which it is applied. The forward end of the buckle is prevented from slipping out

of its grooved seat in the link by the lug 7^a in said link extending over the forward part of the buckle. The stretching action of the tool forces the free end of the band which has been passed through the opening 70 in the buckle farther therethrough and when the band is sufficiently tight, said end is bent about the inclined edge of the opening in the buckle and then against the exterior inclined edge and so beneath the buckle and 75 band.

That form of the tool which is particularly adapted for stretching or tightening bands without buckles, and shown in Fig. 5, comprises a lever 6^a, a link 7^a pivoted thereto 80 at 9^a, an anvil 15^a, a reciprocating bolt 18^a guided in perforated lugs or brackets 29, 30, a spring 25^a for normally retracting the bolt or pin 18^a and a handle 21^a pivoted at 22^a upon the lever, which parts operate in much 85 the same way as the similar parts of the form of tool shown in Figs. 1 to 4 inclusive. It is necessary, however, to modify the form of the holding means upon the link in order to adapt it to grip the bale band instead 90 of receiving the buckle. For this purpose the link 7^a is formed with a lateral support or anvil 31 adapted to be inserted between the end of the band to be grasped thereby and the box and a dog 32 is pivoted to the link above 95 said support at 33 and formed with a sharpened end 34 adapted to engage the band. It will be noted that any relative movement under tension between the gripped end 35 of the band and the link only tends to cause 100 the dog to grip the band the tighter by reason of the position of the pivot with reference to the support and the length of the dog. A handle 36 facilitates swinging the dog against spring 42 when desired. As it 105 is desirable in fastening the ends of the band together that the operator have both hands free, I have provided means for maintaining the link and lever in the position to which they are carried when the desired 110 tension has been put upon the band. For this purpose a ratchet bar 37 is pivoted upon the same pivot 33 which carries the dog and extends in the general direction of the link but beyond the lever where it is formed with 115 a series of ratchet teeth 38 and a handle 39. The pivoted handle 21^a by which the bolt 18^a is operated is in this case prolonged beyond its pivot into an arm 40 which is perforated at its lower end at 41 to receive 120 the end of the ratchet bar 37. In operation the dog and support upon the link are first caused to engage one end of the band and the anvil 15^a upon the lever engaged beneath the other end of the band. By gripping the 125 pivoted handle 21^a the bolt 18^a is caused to engage the band upon the anvil 15^a and grip the same, and the lever is then pressed to the right, as shown in Fig. 5.

The pressure on the handle 21^a and the 130

motion thereof with that of the main lever 6^a to the right feeds the latch bar 37 through the opening 41 in the arm 40 and therefore when the band is sufficiently stretched and 5 the pressure on the tool is released it maintains its position freeing the hands of the operator to secure the ends of the box band together. Obviously the ratchet bar shown in Fig. 5 could readily be applied to that 10 form of the device shown in Fig. 1.

I claim:

1. In a device of the class described, a lever having an anvil thereon, a reciprocating bolt adapted to engage a band on said anvil, a handle pivoted to the lever and adapted to engage one end of the bolt to drive the other end into engagement with the anvil or a band thereon, and a link pivoted to the lever and having means to engage the other end of a box band.
2. In a device of the class described, a lever having an anvil thereon, a bolt reciprocable longitudinally of the lever toward and from the anvil, a spring surrounding 25 the bolt and normally maintaining the end thereof spaced away from the anvil, a handle pivoted to the lever and engaging the end of the bolt, and a link connected to the lever and having means for engaging the 30 other end of the box band.
3. In a device of the class described, a lever having an anvil formed thereon, a reciprocating bolt coöperating with the anvil to engage the end of a box band, a handle

for reciprocating the bolt pivoted to the 35 lever, a link pivoted to the lever on the same side thereon as the pivoted handle, and means on the link for engaging the other end of the box band.

4. In a device of the class described, a 40 lever, means on the lever for engaging an end of a box band, a link pivoted to the lever and formed with a cross head, there being a transverse groove in the cross head 45 adapted to engage the edge of a band buckle.

5. In a device of the class described, a lever, means on the lever for engaging an end of a box band, a link pivoted to the 50 lever and formed with a cross head, there being a transverse groove in the cross head adapted to engage the edge of a band buckle, and a projection 7^a adapted to engage a buckle being operated upon and maintaining 55 the proper position.

6. In a device of the class described, a lever, means on the lever for engaging an end of a box band, a link pivoted to the lever and formed with a cross head, there 60 being a transverse groove in the cross head adapted to engage the edge of a band buckle, and a slot in said head extending longitudinally of the link.
